(57) CLAIM

The ornamental design for a mattress cover, as shown and described.

DESCRIPTION

FIG. 1 is a front perspective view of a mattress cover showing the new design, and is shown after being expanded to cover a mattress;

FIG. 2 is a rear perspective view thereof;

FIG. 3 is a top view thereof; the bottom view is the same as the top view shown;

FIG. 4 is a right side view thereof;

FIG. 5 is a left side view thereof;

FIG. 6 is a front view thereof; and,

FIG. 7 is a rear view thereof.

1 Claim, 5 Drawing Sheets
